UNITED STATES PATENT OFFICE.

HARRY E. BECKER, OF BREA, CALIFORNIA, ASSIGNOR TO REGAN FORGE AND ENGINEERING COMPANY, INC., OF SAN PEDRO, CALIFORNIA, A CORPORATION OF CALIFORNIA.

COMBINATION CORE BARREL AND REAMER.

Application filed March 7, 1923. Serial No. 623,555.

To all whom it may concern:

Be it known that I, HARRY E. BECKER, a citizen of the United States of America, residing at Brea, in the county of Orange and State of California, have invented new and useful Improvements in Combination Core Barrels and Reamers, of which the following is a specification.

My invention relates to a combination core barrel and reamer, adapted to be used in the drilling of oil wells, and contemplates the provision of a tool having a novel form of core barrel, whereby a core may be formed for the purpose of determining the geological formations, and at the same time to enlarge the diameter of the bore sufficiently to admit of the introduction of a well casing.

In the construction of core barrels, it has heretofore been customary to so assemble the parts as to cause the core barrel to revolve in unison with the core bit and reamer. By the employment of core barrels of this type it has been found that difficulty is experienced in obtaining perfect cores, the frictional contact between the revolving inner peripheral wall of the core barrel and the outer peripheral wall of the core, being sufficient to break and disintegrate the core, this being particularly true when the formation is of a crumbly nature, thus rendering it extremely difficult to analyze the disposition of the various formations.

It is the object of my present invention to provide a novelty core barrel construction in which the barrel will remain stationary with respect to the core, thus eliminating the torsional strain on the core and permitting of its removal intact from the barrel.

Another object of my invention is to provide a core barrel formed in segments, which may be conveniently separated, in order that the core may be removed from the same without danger of its becoming broken or disintegrated during this operation.

The above and other objects of my invention will be more fully set forth in the following specification, reference being had to the accompanying drawings, in which:

Fig. 1 is a vertical section through a tool embodying the features of my invention.

Fig. 2 is an enlarged detail vertical section through the core barrel.

Fig. 3 is a transverse section through the core barrel taken on the line 3-3 of Fig. 1.

In carrying out my invention, 5 represents the reamer bit stock having the bore 6, in the lower end of which is threaded the core bit 7. To the lower end of the bit stock 6 are secured the removable reamer cutting blades 8, which surround the core bit 7, the cutting edges thereof being disposed above the cutting edges of the core bit as clearly shown in Fig. 1 of the drawings.

Threaded to the top of the reamer bit stock 5 is the subbushing 8' adapted, in turn, to be secured to the usual drill collar (not shown).

Threaded into the top of the reamer bit stock 5 is a cap member 9 which extends upwardly into the bore of subbushing 8' to protect the core barrel from the wash water.

Threaded into the top of the core bit 7 is a core barrel bearing tube 10 which extends upwardly through the bore 6 of reamer bit stock 5, and into the cap member 9, said tube being provided with top and bottom ball bearings 11 and 12, in which is journaled a core barrel 13, said core barrel being held in vertical adjustment by means of a cap member 14 threaded to its top end, and a nut 15 threaded to its lower end.

The core barrel is preferably formed in segmental halves, 16 and 17, as shown, in order that when removed from the well it may be conveniently opened for the removal of the core. The cap 14 is provided with a valve 18 for the relief of air pressure above the core as it is being formed, and in order that the air may readily escape into the well, the passages 19 are formed in the reamer bit stock 5 and communicating with the bore thereof which in turn communicates with the core barrel when said valve is opened.

The usual wash water for the bits passes through the subbushing 8' through the annular passage 20 formed between the same and the cap 9, and from thence through the passage 21 and discharges adjacent the bit blades.

In operation, the core and reamer bits are rotated in unison in the usual manner, the core progresses upwardly in the core barrel, and as the core barrel is journaled to revolve independently of the bits when it comes in contact with the core, it will remain sta-

tionary therewith, and consequently there will be no tendency to twist the core and break or otherwise damage the same.

After the core has been formed, the device is removed from the well with the core in the barrel, the bearing tube 10 is disconnected from the core bit stock, and the various other threaded joints are disconnected, thus permitting of the separation of the segments forming the core barrel to permit of the core being removed without damage.

What I claim is:

1. A rotary core drill comprising an outer tubular member having a plurality of vertically disposed reamer cutting blades secured to the end thereof, an annular boring bit detachably secured to the lower end of the tubular member and below the reamer blades, a sectional core barrel mounted within said tubular member for relative rotation therewith, and a valved cap for said core barrel, a cap member of greater diameter than said core barrel secured to and within said tubular member, whereby to protect the core barrel from wash water during the operation of the drill, said tubular member provided with fluid outlets leading from the hollow cap and tubular member to the exterior surface of the tubular member adjacent the boring bit and reamer blades.

2. A rotary core drill comprising a tubular

member formed in two sections, the lower of said sections being provided with a detachable boring bit and a plurality of reamer blades disposed thereabove, a core barrel mounted in the lower of said sections for relative rotation with said tubular member, said core barrel provided with an air relief valve, and a hollow cap member secured to said lower member and surrounding the upper end of said core barrel.

3. A rotary core drill comprising a hollow outer member provided in its peripheral wall at the lower end with a plurality of reamer blades, a hollow core bit detachably secured to the lower end of said outer member, a core barrel bearing tube detachably secured to the hollow core bit, and a core barrel journaled in said bearing tube.

4. A rotary core drill comprising a hollow outer member provided in its peripheral wall at the lower end with a plurality of vertically disposed reamer blades, a hollow core bit detachably secured to the lower end of said outer member, a core barrel bearing tube detachably secured to said hollow core bit, and a sectional core barrel mounted within the core barrel bearing tube for relative rotation therewith.

In witness that I claim the foregoing I have hereunto subscribed my name this 27 day of January, 1923.

HARRY E. BECKER.
